TIE RACK

Melvin Reese Baker and Dewayne Kenneth Williams, Anaheim, Calif., assignors to Williams Manufacturing Co. Inc., Anaheim, Calif., a corporation of California

Application September 15, 1952, Serial No. 21,471

Term of patent 14 years

(Cl. D33—8)

To all whom it may concern:

Be it known that we, Melvin Reese Baker and Dewayne Kenneth Williams, both citizens of the United States and both residing at Anaheim, in the county of Orange, State of California, have invented a new, original, and ornamental Design for a Tie Rack, of which the following is a specification, reference being had to the accompanying drawing, forming a part hereof.

Figure 1 is a perspective view of a tie rack embodying our new design;

Fig. 2 is a view in front elevation of the same;

Fig. 3 is a top plan view of the same; and

Fig. 4 is an end view in elevation of the same.

We claim:

The ornamental design for a tie rack, substantially as shown.

MELVIN REESE BAKER.
DEWAYNE KENNETH WILLIAMS.
